Rees Moss, Philadelphia, Penn.

Letters Patent No. 2480, Dated Oct. 2, 1866

Design for the Plates of a Star Cooking Range.

The Schedule referred to in these Letters Patent and making part of the same.

To all whom it may concern.

Be it known that I, Reed Moss of Philadelphia, County of Philadelphia, State of Pennsylvania, have invented or produced a new and original Design for the Plates of the Star Cooking Range, and I do hereby declare the accompanying drawing, with the following explanation of the same to form a full, clear and exact description of the said Design.

The Figure in the accompanying drawing represents the front plates of the Star Cooking range. To the front plate are hung the oven doors B, B, the fire box doors C, C, and ash-pit doors D, D,

227
On the doors C, C, is the usual lock opening which is covered by a lid B, and below the doors D, D, is a register E. On each side edge of the plates is an oblong panel with rounded ends in which are three stars.

Each door B, is bordered by a plain moulding and in the centre is an oval panel containing a large star and in each corner of the door is a small star. Each of the doors C, C, D, D, is bordered by a plain edging, contains an oval panel, and has in each corner a small star. On the lid E, are two stars, between which is the word star.

I claim the Design for the plates of the Star Cooking Range, substantially as shown in and by the accompanying drawing.

In testimony whereof I have signed my name to this Specification in the presence of two subscribing witnesses.

Witnessed,

Charles E. Foster,

John White.

Rees Moss.
